VARIABLE CAPACITY HYDRAULIC PUMP

Claude J. Christopher, Los Angeles, Calif.

Application December 5, 1947, Serial No. 789,827

3 Claims. (Cl. 103—174)

1

This invention relates to a variable capacity hydraulic pump.

It is an object of the present invention to provide in a hydraulic pump a simple mechanism for adjusting the stroke of a plurality of circumferentially disposed pump pistons.

Other objects of the present invention are to provide a variable capacity pump which is of simple construction, easy to adjust, inexpensive to manufacture, durable, compact, has minimum parts and is efficient in operation.

For a better understanding of the invention, reference may be had to the following detailed description taken in connection with the accompanying drawing, in which

Fig. 1 is a transverse sectional view taken through the pump employing the adjusting mechanism of the present invention,

Fig. 2 is a fragmentary cross-sectional view taken on line 2—2 of Fig. 1 and looking in section upon the adjusting plate,

Fig. 3 is a vertical sectional view of the pump as viewed on line 3—3 of Fig. 1,

Fig. 4 is a fragmentary and detail view taken through the projections of the adjusting plate and on line 4—4 of Fig. 1,

Fig. 5 is a detail side view, in elevation, of one of the connecting links,

Fig. 6 is a transverse cross-sectional view similar to Fig. 1 but showing the adjustable plate with the linkage connections to the driving plate and piston adjusted to different positions than shown in Fig. 1,

Fig. 7 is a fragmentary and sectional view taken on line 7—7 of Fig. 6.

Referring now to the figures, 10 represents a housing part to which is connected plates 11 and 12. The plate 11 has a large hub portion 13 and a bearing sleeve 14 therein for supporting a shaft 15. A packing nut 16 retains a packing ring 17 within the hub portion 13. The plate 11 is secured to the housing part 10 by large screws 18.

The plate 12 has a bearing sleeve 19 in which is journaled a projection 21 of the shaft 15. The shaft is retained against displacement from the plate 12 by a cotter pin 22 extending through the shaft projections 21 and a lock nut 23. The plate 12 can be adjusted in the casing part 10. A handle portion 24 extends from the plate 12. A pull pin 25 is extended through the handle portion 24 and into any one of a plurality of adjusting holes 26 in the housing part 10 so that the plate can be retained in any one of several angularly adjusted positions.

The shaft 15 has an enlarged eccentric portion

2

27 on which is mounted a driving plate 28. This driving plate has a projection 29 extending radially therefrom for connection with a piston rod 31 of a piston 32 operable in a pump cylinder 33. Each pump cylinder is provided with fluid conduits 34 and 35 having conventional intake and exhaust valves 34' and 35', respectively. The cylinder 33 is flanged at 36 and is secured to the housing part 10 by fastening screws 37.

On the plate 12 are a plurality of anchor projections 38 extending inwardly from the inner face of the plate 12 and are adapted to respectively receive a pair of slotted arcuate shaped links 39. These links 39 serve to connect the projection 29 with the piston rod 31. Between the links there is extended a slide 41 to which piston rod 31 is connected by a pin 42. The slide 41 works in the slots of the arcuate shaped links and between the respective links. Since the driving plate 28 is on an eccentric, the driving plate 28 will oscillate and will through the arcuate shaped links 39 move the piston 32 upwardly. The length of stroke will depend upon the distance to which the slide 41 is located from the connection of the arcuate links 39 with the anchor portion 38.

The driving plate 29 has a different means for its connection with the piston rod of the other pistons. Projections 44 thereon are provided with a pivot link 45, Fig. 5, so as to permit a rocking movement of the arcuate shaped members 39 connected to the member 45. The pivotal connection between the member 45 and the arcuate members 39 is indicated at 46. The anchor portion 38 has a top part 48 into which a pivot pin 49 is extended. The bottom link 39 is connected to the plate 12 by a pivot pin 50, Figs. 4 and 7.

It will be apparent that as the shaft 15 is driven the pump pistons 32 will be operated. While this mechanism has been described as a pump it will be apparent that it can be utilized as a power transmission unit and the control therefor serving to alter the output speed of the transmission.

While various changes may be made in the detail construction, it shall be understood that such changes shall be within the spirit and scope of the present invention as defined by the appended claims.

I claim:

1. A hydraulic pump comprising a housing, pump cylinders radially arranged in the housing, pistons operable in the pump cylinders, a shaft extending into the housing and having an eccentric portion thereon, a driving plate connected to the eccentric portion, an adjustable plate forming a part of the housing and having anchor por-

tions thereon, slotted links pivotally connected to the anchor portions, a slide operable between the slotted links, a piston rod connected to the slide, and a connection between the driving plate and the slotted links to operate the same and to effect the movement of the pistons.

2. A hydraulic pump comprising a housing, pump cylinders radially arranged in the housing, pistons operable in the pump cylinders, a shaft extending into the housing and having an eccentric portion thereon, a driving plate connected to the eccentric portion, an adjustable plate forming a part of the housing and having anchor portions thereon, slotted links pivotally connected to the anchor portions, a slide operable between the slotted links, a piston rod connected to the slide, and a connection between the driving plate and the slotted links to work the same and to effect the operation of the pistons, and connection between the driving plate and the slotted links being a pivoted link connector and serving to move the slotted links radially inwardly and outwardly.

3. A hydraulic pump comprising a housing, pump cylinders radially arranged in the housing, pistons operable in the pump cylinders, a shaft extending into the housing and having an eccentric portion thereon, a driving plate connected to the eccentric portion, an adjustable plate forming a part of the housing and having anchor portions thereon, slotted links pivotally connected to the anchor portions, a slide operable between the slotted links, a piston rod connected to the slide, and a connection between the driving plate and the slotted links to operate the same and to effect the movement of the pistons, and said adjustable plate having a handle portion thereon, said housing having a plurality of adjusting holes and a pull pin insertable through the handle and into any one of the adjusting holes of the housing.
